(57) **CLAIM**

The ornamental design for nested containers, as shown and described.

DESCRIPTION

FIG. 1 is a perspective view of the nesting containers shown in an opened position;

FIG. 2 is an exploded perspective view shown in FIG. 1;

FIG. 3 is a cross-sectional view taken along line 3-3 of FIG. 9

FIG. 4 is a perspective view of an embodiment of a first

container of the claimed design;

FIG. 5 is a front elevational view thereof;

FIG. 6 is a back elevational view thereof;

FIG. 7 is a left side elevational view thereof;

FIG. 8 is a right side elevational view thereof;

FIG. 9 is a top view thereof;

FIG. 10 is a bottom view thereof;

FIG. 11 is a back elevational view thereof;

FIG. 12 is a perspective view thereof with the lid open;

FIG. 13 is a perspective view thereof with the lid open;

FIG. 14 is a top view thereof with the lid open;

FIG. 15 is a perspective view of an embodiment of a second

container of the claimed design;

FIG. 16 is a front elevational view thereof;

FIG. 17 is a back elevational view thereof;

FIG. 18 is a left side elevational view thereof;

FIG. 19 is a right side elevational view thereof;

FIG. 20 is a top view thereof;

FIG. 21 is a bottom view thereof; and,

FIG. 22 is a top view thereof with the lid open.

The broken lines showing a latch, longitudinal strap, power cord and opening bracket are for the purpose of illustrating environment and form no part of the claimed design.

The containers are shown separately for ease and clarity of illustration.

1 Claim, 22 Drawing Sheets
